UNITED STATES PATENT OFFICE.

CHARLES S. BUSHNELL, OF ROCHESTER, NEW YORK, ASSIGNOR TO GENERAL RAILWAY SIGNAL COMPANY, OF ROCHESTER, NEW YORK.

TRAIN CONTROL.

Application filed July 25, 1924 Serial No. 728,186.

This invention relates to automatic train control systems, and more particularly to improvements in car-carried control apparatus for such systems whereby continuous operation of the driving mechanism of such apparatus may be insured.

In train control practice, control influences corresponding to traffic conditions ahead are usually communicated by suitable means from the trackway to control apparatus carried on the vehicle. This control apparatus ordinarily includes several devices, including a speed responsive device, which devices are driven from the car wheels by suitable means. In order that this control apparatus may be reliable, and may at all times reflect the speed and progress of the train, it is desirable that the drive or transmission for this speed responsive device and the other driven control devices be checked, so that any failure of such driving apparatus may be brought to the attention of the engineer or train operator.

It is an object of this invention to provide a means for checking the drive of the car-carried control apparatus and for bringing the vehicle to a stop if such drive should fail.

Further objects and advantages of the invention will be pointed out or will become apparent as the description progresses.

In the drawings, the car-carried apparatus of a system embodying this invention has been shown in a diagrammatic and simplified manner.

The system shown is of the type which acts to impose more and more restrictive speeds as the vehicle progresses from a point at which certain control influences are received, although it is to be understood that many other types of control systems employing devices driven from the car wheels may be used in connection with the present invention.

In the particular system shown, a main car relay MR having two movable contact fingers 1 and 2 is provided. This relay may be of the two-position single phase type, as shown, but any other type of relay may be employed if desired. In the type of relay shown, the contact fingers 1 and 2 are preferably biased by springs or weights to assume a definite position upon de-energization of the relay wind-

ings. These contact fingers 1 and 2 are also preferably mounted on vertically arranged axes so as to be unaffected by the vibration or swaying of the train. It is assumed that the main relay MR is connected by means of the wires 3 and 4 to suitable receiving devices located on the vehicle, and arranged to respond to control influences transmitted from suitable trackway apparatus. The receiving equipment may include an amplifying device, and the input circuit to said amplifying device may be resonated by means of a condenser if desired.

The particular trackway apparatus and the associated car-carried receiving devices may be of any suitable type and have for convenience not been illustrated in the drawings, as the operation of such apparatus and devices is well known to those skilled in the art, and as the specific form of transmitting means used forms no part of the present invention.

A drive shaft 5 is provided, and is geared or otherwise suitably driven from the wheels and axles of the vehicle. This shaft carries a worm gear 6, and a speed responsive device. The speed responsive device may comprise any one of a number of suitable types. In the embodiment chosen for the purpose of illustration, a simplified speed responsive device has been shown, taking the form of a centrifuge G. This centrifuge comprises a fixed collar 7 and a movable collar 8, urged apart by a spring 9, the collar 8 being drawn downward upon rotation of the shaft 5 by centrifugal force acting upon the links and weights 10 and 11. The collar 8 engages an arm 12, fixedly secured to speed shafts 13, as shown, so that the shaft 13 is rocked in proportion to the speed at which the vehicle is traveling. It should be noted that the fixed collar 7 and the worm gear 6 are intimately associated, preferably being made integral, so that the possibility of a break in the driving mechanism between this worm gear 6 and the centrifuge G is very remote.

The worm gear 6 operates the distance shaft 14 through a train of gears and an electrically operated gear engaging arm 15, as shown. The arm 15 is normally held in the disengaged position by means of the cam starter magnet 16.

CS, and when this magnet is de-energized, the spring 16 places the arm 15 in the engaged position. The distance shaft 14 is driven through a mutilated gear 17 and is returned to its normal position by a spring 18 upon the disengagement of the gear train just described.

The speed shaft 13 and the distance shaft 14 may carry any number of cams or other devices for operating the car-carried control apparatus. In the simplified embodiment shown, a single speed cam 19 is provided on the speed shaft 13, and a distance cam 20 and permissive speed cam 21 are provided on the distance shaft 14. The speed cam 19 operates the resilient contact fingers 22, biased to the opened position, the cam 19 being designed to open these contact fingers at speeds from zero to 15 miles per hour only. The distance cam 20 operates the resilient contact fingers 23 similar to those just described, and is designed to close these contact fingers as soon as the distance shaft 14 is operated. The permissive speed cam 21 operates one end of a floating lever 24, the other end of which is moved by the lever 25, in proportion to the rocking of the speed shaft 13. It is evident that the movement of an intermediate point on this floating lever 24 will be determined by a function of the vehicle speed and its distance of travel from the point at which the distance shaft 14 is initiated. The floating lever 24 operates a contact sector 26 through a link 27, this contact cam being normally biased by the spring 28. The sector 26 operates the resilient contact fingers 29, which are normally biased to their open position, and allows these contact fingers to open under certain conditions of speed and distance of vehicle travel from a point at which certain control influences were received.

A control relay CR is provided, this relay being preferably of the slow acting type for reasons which will become apparent as the description progresses. This slow acting feature may be obtained by employing a copper sleeve around the relay core to sustain the flux therein, or any other suitable means may be employed to obtain the desired result. The control relay CR is provided with a movable contact finger 30, and a stationary front contact, conventionally represented by the arrow 31. The contact finger 30 is biased to disengage the front contact 31 a predetermined time after the de-energization of the windings of the relay CR.

Suitable means are provided for applying the brakes of the train in response to control influences. These means may take the form of a valve for venting the brake pipe directly, or may consist of a device for operating the regular engineer's brake valve. In the simplified form shown, an electro-pneumatic valve EPV is provided, it being assumed that this electro-pneumatic valve will act in some

suitable manner to apply the brakes of the vehicle when its winding is de-energized.

In order to simplify the drawings and the explanation of the operation of the system, the letters B and C have been used to represent the opposite poles of a source of electrical energy which may be the terminals of a battery.

Operation.—Before explaining the operation of the check for the control apparatus 75 drive which comprises the present invention, a brief description of the operation of the simplified and typical train control system shown will be given.

In the usual train control system, dangerous traffic conditions ahead, such as a train, a broken track rail, an open switch or other hazard in the block in which the train is located, or in the next block in advance, are usually arranged to so affect the receiving devices as to cause the de-energization of the main car relay MR. In the drawings, all devices have been shown in their normal positions, that is, the positions assumed with the train running at speed under clear traffic 90 conditions. Assuming that a train equipped with a control system of the type illustrated is proceeding under clear traffic conditions, that is, with no train or other hazard in the block in which the train under consideration 95 is traveling or in the next block in advance, and with the train speed above 15 miles per hour but not excessive, the main relay MR will be energized, attracting its contact fingers 1 and 2. The contact finger 1 closes a circuit 100 to the cam starter magnet CS through the contact fingers 22 of the speed cam 19, and the contact finger 2 of the main relay MR closes a circuit to the control relay CR, which circuits are obvious from the drawings. The energization of the cam starter magnet CS 105 maintains the gear train disengaged, and the distance shaft 14 is therefore in its initial biased position as shown. The energization of the control relay CR closes the front contact 31 of this relay, so maintaining an energizing circuit to the electro-pneumatic valve EPV through the contact finger 29 of the sector 26, which circuit is obvious from the drawings. With the electro-pneumatic valve 110 EPV energized, the train may proceed in the clear block for reasons heretofore given.

As the speed of the train increases, the speed shaft 13 moves the sector 26 through the arm 25, the floating lever 24 and the link 27, and if a maximum speed limit of, say 60 miles per hour, is exceeded, the contact fingers 29 are opened and the energizing circuit to the electro-pneumatic valve EPV is broken, causing an automatic brake application which continues until the train speed has been reduced below the maximum speed limit assumed to be 60 miles per hour, when the electro-pneumatic valve is again energized by the closing 125 of the contacts 29 of the sector 26.

If the train enters a block in which caution traffic conditions exist, the main relay MR becomes de-energized, retracting its contact fingers 1 and 2, and so opening the front contacts of these fingers. The opening of the front contact of finger 1 de-energizes the cam starter magnet CS, causing the engagement of the gear train and the starting of the distance shaft 14. As soon as the distance shaft 14 starts, the cam 20 closes its contact fingers 23, energizing the control relay CR through a circuit which includes these fingers 23 and the wire 33 as shown. As the distance shaft 14 continues to rotate, the permissive speed cam 21 moves the floating lever 24, imposing more and more restrictive speed limits through the cam 26 and its associated contact fingers 29. After the distance shaft 14 has been rotated through approximately 180°, its further rotation will be prevented by the mutilated portion of the mutilated gear, and a minimum speed limit will be set up by the permissive speed cam 21. This minimum speed limit is assumed in the present embodiment to be 20 miles per hour. If the restrictive speed limit is exceeded, the sector 26 will open its contact fingers 29, de-energizing the electro-pneumatic valve EPV and causing an automatic brake application which continues until the train speed has been reduced to a value below that of the restrictive limit which is set up by the permissive speed cam and associated mechanism. The opening of the front contact of finger 2 of the main relay MR breaks a circuit to the control relay CR, but this control relay is immediately re-energized through the contact finger 23 of the cam 20 as explained above, and as this control relay CR is slow acting, its contact finger 30 will not be retracted by this momentary de-energization of its windings.

When traffic conditions become more favorable, the main relay MR is re-energized, attracting its contact fingers 1 and 2, re-energizing the cam starter magnet CS and allowing the distance shaft 14 to assume its initial position, whereupon the restrictive control through the sector 26 is removed, and the train may proceed at speed. The contact fingers 23 of the distance cam 20 are opened, but the control relay CR is maintained energized through the contact finger 2 of the main relay MR.

Referring now particularly to the operation of the check for the transmission to the control apparatus, which is the essential part of the present invention, assume that a train equipped with the apparatus described is proceeding under clear traffic conditions, and that the drive shaft 5 becomes disengaged from the axles of the vehicle by reason of a break in this shaft or for any other reason. The centrifuge G will immediately assume its zero miles per hour position, opening the contact finger 22 of the speed cam 19 and

thus de-energizing the cam starter magnet CS. The de-energization of the cam starter magnet CS will cause the gear train to be engaged, but no motion of the distance shaft 14 will result for the reason that no power is applied from the drive shaft 5. The contact fingers 23 operated by the distance cam 20 will therefore remain open.

Now assume that the train under consideration with its control apparatus in the condition just described enters a block in which caution traffic conditions exist. The main relay MR will be de-energized, retracting its contact fingers 1 and 2. The retracting of the contact finger 2 of the main relay MR will open the energizing circuit to the control relay CR, de-energizing the windings of this relay and causing the retraction of its contact finger 30 after a given period of time. When the contact finger 30 of the control relay CR disengages its front stationary contact 31, the energizing circuit to the electro-pneumatic valve EPV will be broken, and an automatic brake application will result, bringing the train to a stop. As this automatic stop will be immediate, and will not be preceded by the usual tapered speed restriction described above, the engineer or train operator will be aware of the fact that the drive shaft of the control apparatus is out of order, and will probably cut out the automatic train control apparatus by operating a suitably sealed or otherwise protected cut-out device, the operation of which must be explained and excused at the end of the run. In such cut-out device is not provided, the train must remain at a stop until traffic conditions ahead become more favorable, when the train may proceed with automatic stop control, that is, whenever the train enters a caution or a danger block, it is brought to a stop at once by the de-energization of the control relay CR and the electro-pneumatic valve EPV, controlled by the contact finger 2 of the main relay MR.

Now assume that the train under consideration is proceeding under caution traffic conditions, that is, with the main relay MR de-energized, the cam starter magnet CS de-energized and the distance shaft 14 initiated. Now assume that the drive shaft 5 breaks or otherwise becomes disengaged from the wheels or axles of the vehicle. The distance shaft 14 is immediately returned to its initial biased position, spring 18 being strong enough to return shaft 14 to such position even when the gears of gear train 17 etc. are in mesh, thus opening the contact fingers 23 of the cam 20. The speed arm 12 is raised by the spring 9, causing the shaft 13 to assume its zero miles per hour position, and causing the speed cam 19 to open its contact fingers 22. As the main car relay MR is already de-energized and its contact finger 2 is in the open position, the opening of contact finger 23 of the cam 20 will cause the de-

energization of the control relay CR. After a certain time interval, the control relay CR retracts its contact finger 30, breaking the energizing circuit to the electro-pneumatic valve EPV, and an automatic brake application will result bringing the train to a stop.

Now assume that a train equipped with the apparatus embodying the present invention comes to a stop under clear traffic conditions.

10 When the train speed is reduced to 15 miles per hour, the contact fingers 22 of the speed cam 19 are opened, causing the de-energization of the cam starter magnet CS and the consequent initiation of the distance shaft 14.

15 As the train comes to a stop, the distance shaft 14 will be rotated a slight amount, causing the cam 20 to close its contact finger 23, and maintaining these contact fingers closed so long as the train is at a stop. Now assume that while

20 the train under consideration is at a stop, the traffic conditions in the block in which the train is located change from clear to caution or danger by reason of a train backing into the block, the breaking of a rail, the opening of

25 a switch or any other dangerous condition. The main relay MR will immediately be de-energized, retracting its contact fingers 1 and 2. The retracting of the contact finger 1 will have no effect as the contact fingers 22 in

30 series with the contact finger 1 are already opened. The retracting of the contact finger 2 of the main relay MR will also have no effect, as the control relay CR is maintained energized through a circuit including the contact finger 23 of the distance cam 20. The train may now proceed in a caution block under the restrictive control of the permissive speed cam 21 as described above.

Assume now that a train proceeds in a clear 40 block at a low speed, below 15 miles per hour, for a comparatively long distance. As soon as the train speed drops below 15 miles per hour, the speed cam 19 will operate to open its associated contact fingers 22, de-energizing the cam starter magnet CS and starting the distance shaft 14. When the distance shaft 14 has revolved through 180°, the permissive speed cam 21 will impose a minimum speed limit, assumed to be 20 miles per hour. It 45 should be noted that as the train speed again increases, the cams starter magnet CS will be re-energized at 15 miles per hour and the distance shaft 14 will be returned to its initial position before the train speed reaches 50 20 miles per hour. It is clear from the above that a train cannot be permanently restricted as to speed by reason of the fact that the distance shaft 14 is in its extreme run down position.

60 It is to be understood that the specific check for the driving mechanism which forms the present invention could be applied to many different types of train control systems and that such train control systems may include 65 many features, combinations and additions

not shown and described in the present embodiment without departing from the spirit of the present invention. For instance, a polyphase car relay may be employed, imposing different speed restrictions under caution and danger traffic conditions; means may also be provided for permitting the vehicle to proceed with either end leading, or many other additions or modifications which are optional rather than essential may be made. 70 75

What it is desired to secure by Letters Patent is:—

1. In an automatic train control system, vehicle carried brake control apparatus including a restrictive speed device imposing 80 a restrictive brake control in response to unfavorable traffic conditions ahead, means for driving elements of said restrictive speed device in accordance with the motion of the vehicle, means for imposing a brake application if said driving means stops, and further means speed initiated and operated in accordance with the train, for preventing said brake application if said driving means has stopped because of a lack of motion of the 85 vehicle.

2. In an automatic train control system, vehicle carried apparatus comprising a control means responsive to influences corresponding to traffic conditions ahead, a restrictive speed device having an element driven in accordance with the progress of the vehicle, said restrictive speed device being initiated by said control means and acting to impose restrictive speeds under unfavorable traffic conditions ahead, and further means, having parts automatically operated in accordance with progress of the train, for imposing a stop 100 under unfavorable traffic conditions ahead only if said driven element stops while said vehicle is in motion.

3. In an automatic train control system, vehicle carried control apparatus comprising a main relay controlled by influences corresponding to traffic conditions ahead, a restrictive speed device driven in accordance with the motion of the vehicle, a brake control device normally controlled by said restrictive speed device, and means for transferring the control of said brake control device to said 110 main relay if the driving means for said restrictive speed device becomes inactive while the vehicle is in motion.

4. In an automatic train control system, car-carried control apparatus comprising a speed governed device, a distance governed device and a restrictive speed device, means for driving said devices from the car wheels, a brake applying means, normally controlled by said restrictive speed device, and a main 120 control means responsive to influences corresponding to traffic conditions ahead, said main control means and said speed governed device normally acting to control said restrictive speed device, and said distance gov- 125 130

erned device acting to transfer the control of said brake applying means to said main control device under unfavorable traffic conditions ahead, only if said driving means become inactive while the vehicle is in motion.

5. In an automatic train control system, vehicle carried brake control apparatus comprising a brake applying device controlled by a restrictive speed device, means for driving said restrictive speed device in accordance with the travel of the vehicle, a main relay controlled in response to influences corresponding to traffic conditions ahead, and a control relay for actuating said brake applying device from said main relay under favorable traffic conditions ahead if said driving means stops while the vehicle is in motion, said control relay being inactive if said driving means stops due to a stop of the vehicle.

6. In an automatic train control system, vehicle carried control apparatus comprising, a restrictive speed device, means for driving said restrictive device in accordance with the travel of the vehicle, a brake applying device, normally controlled by a circuit including a contact of said restrictive speed device, a main relay controlled in response to influences corresponding to traffic conditions ahead, and a control relay for breaking said circuit to said brake applying device, said control relay being controlled alternatively by a circuit including contacts of said main relay and contacts of a distance governed element associated with said control device.

7. In an automatic train control system, vehicle carried brake control apparatus comprising a brake applying device, normally controlled by a restrictive speed device, means for driving said restrictive speed device, when initiated, in accordance with the travel of the vehicle, control means for initiating said restrictive speed device when influences corresponding to unfavorable traffic conditions are received from the trackway, and means for causing an immediate operation of said brake control apparatus if the drive of said restrictive speed device stops while the vehicle is travelling under unfavorable traffic conditions, and means for preventing such brake application if the drive stops under favorable traffic conditions.

8. In an automatic train control system, a normally energized brake applying device adapted to cause an automatic brake application when de-energized, a restrictive speed device including a speed responsive element and a distance operated element, both of said elements being driven in accordance with the travel of the vehicle, said restrictive speed device acting when initiated to de-energize said brake applying device if the vehicle speed exceeds a predetermined value, a main relay, energized in accordance with favorable traffic conditions and de-energized in re-

sponse to unfavorable traffic conditions ahead, and acting when de-energized to initiate said restrictive speed device, a control relay, acting when de-energized to de-energize said brake applying device, said control relay being energized by the energization of said main relay and being energized if said distance element of said restrictive speed device is initiated, and means for initiating said distance element of said restrictive speed device whenever the speed responsive element of said device indicates a predetermined low speed.

9. In an automatic train control system, vehicle carried brake control apparatus comprising a brake applying device normally controlled by a restrictive speed device, means for driving said restrictive speed device, when initiated, in accordance with the travel of the vehicle, control means for initiating said restrictive speed device when influences corresponding to unfavorable traffic conditions are received from the trackway, and means for causing an immediate operation of said brake control apparatus only if the drive of said restrictive speed device stops while the vehicle is under unfavorable traffic conditions.

10. In an automatic train control system, vehicle carried brake control apparatus comprising a brake applying device normally controlled by a restrictive speed device, means for driving said restrictive speed device when initiated, in accordance with the travel of the vehicle, control means for initiating said restrictive speed device when influences corresponding to unfavorable traffic conditions are received from the trackway, other means for causing an immediate operation of said brake control apparatus if said drive means be inoperative under unfavorable traffic conditions, and means to prevent such immediate brake operation while the vehicle is travelling under favorable traffic conditions.

11. In an automatic train control system, vehicle carried brake control apparatus comprising a brake applying device normally controlled by a restrictive speed device, means for driving said restrictive speed device, when initiated, in accordance with the travel of the vehicle, control means for initiating said restrictive speed device when influences corresponding to unfavorable traffic conditions are received from the trackway, means for causing an immediate operation of said brake control apparatus only if said drive means stop under unfavorable traffic conditions, and automatically operated means to prevent such immediate brake operation if stop of the said drive be due to stopping of the vehicle.

12. In an automatic train control system, vehicle carried brake control apparatus comprising a brake applying device normally controlled by a restrictive speed device,

means for driving said restrictive speed device, when initiated, in accordance with the travel of the vehicle, control means for initiating said restrictive speed device when influences corresponding to unfavorable traffic conditions are received from the trackway, means for causing an immediate operation of said brake control apparatus if said drive means stop under unfavorable traffic condi-

tions and to prevent such immediate brake operation if the vehicle be travelling under favorable traffic conditions, and automatically operated means to prevent such immediate brake operation if stop of the said drive be due to stopping of the vehicle. 10 15

In testimony whereof I affix my signature.

CHARLES S. BUSHNELL.
